STOCK FEEDING APPLIANCE

Jess A. Powell, San Antonio, Tex.

Application July 24, 1947, Serial No. 763,277

2 Claims. (Cl. 119—53.5)

1

This invention relates to stock feeding apparatus.

It is an object of the present invention to provide stock feeding apparatus which is made up of several parts, which may be formed of concrete or the like and which can be assembled upon a base to provide a feeding trough, a feed containing cylinder, a cover over the feeding trough, a cover over the feed containing cylinder and means at the bottom of the feed container for controlling the flow of feed into the feeding trough.

It is another object of the present invention to provide a feeding apparatus of the type described, which is of circular shape, having means on the supporting feed trough base which will extend outwardly into the trough so that it can be moved by the nose of the stock as they are feeding, whereby to keep the feed from caking or bridging the interior of the feed container and whereby to maintain a constant flow of feed through the opening.

Other objects of the present invention are to provide a stock feeding apparatus which is of simple construction, easy to install, inexpensive to manufacture and efficient in operation.

For other objects and for a better understanding of the invention, reference may be had to the following detailed description taken in connection with the accompanying drawing, in which:

Figure 1 is a fragmentary top plan view, partly in section and partly broken away, of a stock feeding apparatus embodying the features of the present invention;

Figure 2 is an elevational view, partly in section, of the stock feeding apparatus with portions broken away about the feeding trough;

Figure 3 is a cross-sectional view substantially on line 3—3 of Figure 2;

Figure 4 is a vertical cross-sectional view of a modified form of the invention;

Figure 5 is a fragmentary perspective view looking upon the interior cone formation on the feed trough shown in Figure 4 and mounted thereon, the device for maintaining the constant flow of feed into the feed trough, the cone base being modified to adapt the construction for coarser ground feed;

Figure 6 is a detailed view of one of the arms of the agitating device which extends through the side of the feed container for engagement by the nose of the animal and

Figure 7 is an enlarged fragmentary and perspective view showing the ring to which the element is attached interiorly of the feed container

and the conical saddle carrying the ring by which it is retained upon the top of the cone formation.

Referring now to Figures 1 to 3, inclusive, 10 represents a tubular base on which a circular feed trough 11 is mounted. This feed trough has formed integral therewith, an upwardly tapered conical feed distributor 12 in the center of the feed trough over which there is mounted the lower end of a tubular feed container or hopper 13. This feed container 13 has an upwardly bevelled inner marginal edge 14, Figure 2, which closely contacts the wall of the feed distributor 12 and conforming thereto, prevents lateral movement of the hopper 13 on the distributor 12. The lower end of the hopper is also provided with vertical elongated, relatively spaced openings 15 through which the feed will pass to the feeding trough 11. The rate of flow of the feed to the trough 11 is controlled by a gate or ring 16, which surrounds the lower end portion of the hopper 13 and has slots 17 therein extending upwardly from the bottom edge thereof. The gate 16 is rotatable with relation to the hopper 11 so that its slots 17 may be moved into or out of alignment with the slots 15 in the hopper 13. The gate or ring 16 is provided with an outwardly extending handle 18 to facilitate the rotation thereof.

On the top of the feed container 13, there is mounted a circular cover plate 19 adapted to overhang the trough and prevent water from dripping into the same. This cover has an upwardly extending flange over which a feed container cover 21 is extended, so as to keep the water from entering the feed container. The flange is not shown in Figure 1 but it is of the same configuration as flange 20' to be later described, and shown in Figure 4.

In the modified form of the invention for the coarser ground feed shown in Figures 4 and 5, it will be noted that the trough 11' is provided with a depending circular shoulder 22 which engages within the upper end of the base 10' to prevent the trough 11' from sliding off of the base 10' and the trough 11' is of the same configuration as trough 11. The conical feed distributor 12' has a cavity 23 therein providing a lighter formation than if the distributor were of solid formation, and the distributor 12' is of the same configuration as the distributor 12'. The distributor 12' has substantially pentagonal shaped ribs or projections 24 circumferentially spaced therearound and extending upwardly and below these projections are the projections 25 having flat support-

ing surfaces 26 on which the feed container or hopper 13' is rested. The feed container 13' has a flat bottom edge 27. Thus the flat edge 21 coinciding with the flat surface 26 and the inner surface of the hopper 13' contacting the flat faces 28 of the projections 24 prevents lateral movement of the hopper 13'. It will be noted from Figure 4 that the upper end of the hopper 13' is provided with an annular shoulder 29 forming an upstanding annular rib 30, and that the shoulder 29 engages the under surface of the plate 19', and the rib 30 is received in the annular groove 31 of the plate 19'. The groove 31 is concentric with the central opening 32 of the plate 19', which permits the filling of the hopper 13' with feed. The flange 20' of the plate 19' connected with the opening 32 enters the annular groove 33 formed by the depending annular ribs 34 and 35 of the cover 21', and thus the plate and cover and hopper are prevented from lateral movement with respect to each other. The formation of the elements 10, 11, 12, 13, 19, 20 and 21 of the apparatus shown in Figures 1 to 3 is of the same configuration of the similarly primed numbered elements of the modification above described.

In both forms of invention, there is mounted on the distributor 12 and 12' an agitating device which includes a conical shaped saddle cap 36 having a ring 37 secured to its bottom edge by the relatively spaced upturned lips 38. To this ring 37, there are connected a plurality of agitating elements 39 which have a hook formation 40 which extends over the ring, and are movable on the ring with the slots 41 formed in the saddle 36 intermediate the lips 38. These agitating elements are retained against displacement on the ring by the lip formations 38. Each one of the agitating elements 39 extends downwardly between the ribs 24 and 25 on the distributor, and are provided with the U-shaped inclined feet 41 which extend outwardly over the floor of the feeding trough and have outwardly extending projections 42 adapted to be engaged by the nose of the animal while eating, so as to be shifted back and forth to free the feed within the container and to cause its downward flow over the feed distributor and between the ribs 24 and 25 through which the particular agitating element is extended. This agitating element 39 has upstanding projections 43 which will project upwardly into the feed for the agitation of the feed. Thus in Figures 1 to 3, the feeder is designed for feeding minerals or fine feed, the gate 16 controlling the amount of feed to be delivered to the trough 11, and the feeder shown in Figures 4 and 5 is designed for a mixture of mineral and protein feeding or a coarser feed. The amount of feed being delivered to the trough is determined by the height of the ribs 25. The higher the ribs, the more feed distributed, and the lower the ribs, the less feed distributed.

There has thus been provided a stock feeder which is adapted for use for feeding stock in the sheds, or on the open range, and more particularly the latter.

The parts comprising the feeder are made of durable material that will withstand all types of weather.

While various changes may be made in the detailed construction, it shall be understood that such changes shall be within the spirit and scope of the present invention as defined by the appended claims.

I claim:

1. In an agitator means for a stock feeding apparatus having a base, a trough mounted on the base having a central conical formation, a feed containing cylinder mounted on the trough, cover means extending over the feed container and the trough to keep the trough free of water, the improvement comprising agitating means including a saddle cone adapted to be supported from the top of the conical formation, a plurality of turned up relatively spaced lips on the periphery of the saddle cone, a ring member supported by said lips, agitating elements connected to the ring intermediate of the turned up lips and extending radially outwardly under the bottom of the feed container and into the trough and adapted to be engaged by the animal while eating from the trough, whereby to cause the agitation of the feed within the container and its outward flow into the trough, and the turned up lips limiting the movement of the agitating elements along the ring.

2. A stock feeding apparatus comprising a tubular base, a trough having a centrally located depending circular flange on the bottom surface thereof to be received in said base whereby said trough is mounted on the base, said trough having a central conical formation, a feed containing cylinder mounted on the trough, and cover means extending over the feed container and the trough to keep the trough free of water, said conical formation having ribs circumferentially spaced therearound to support said feed container and provide openings between said ribs and below the lower edge of said container, through which the feed can be lowered, and agitating means supported from the top of the conical formation and having a plurality of agitating elements respectively extending through the space between the ribs, and extending radially outwardly under the bottom of the feed container and into the trough and adapted to be engaged by the animal while eating from the trough, whereby to cause the agitation of the feed within the container and its outward flow into the trough.

JESS A. POWELL.
